Atty.

UNITED STATES PATENT OFFICE.

DANIEL J. GOLDEN, OF BROCKTON, MASSACHUSETTS.

CLEAT FOR BASEBALL SHOES.

Application filed November 24, 1928. Serial No. 321,678.

This invention relates to a cleat attachable to the tread face of the forepart of a baseball shoe bottom, and having downwardly projecting ground-engaging spurs adapted 5 to prevent endwise and lateral slipping of the tread, the cleat comprising a body adapted to be engaged by rivets attaching it to the shoe bottom, and spurs integral with and projecting from the body. Three 10 spurs are essential, viz, a front spur adjacent the toe end of the tread face and located on the longitudinal median line thereof, and two lateral spurs behind the front spur and located at opposite sides of said median line, 15 the front spur being adapted to prevent endwise slip, and the lateral spurs to prevent side slip.

The lateral spurs should be located forward of the salient curve at the ball portion 20 of the tread face, in order that they may project from the portion of the tread face which extends forward from the ball portion, and is maintained substantially flat by the usual thin steel plate interposed between 25 an outer and inner layer of the shoe bottom, the rear end of said plate extending into the ball portion.

Heretofore in a cleat of this character, the cleat body has been of substantially triangular form, its rear end extending between the two lateral spurs and being entirely forward of and spaced from the curved ball portion, so that the latter is exposed to wear and is liable to be worn away by the rough usage 35 to which the shoe is subjected, until an opening is formed through which the rear end of the stiffening plate protrudes. The effective life of a baseball shoe in many cases, is materially shortened by this liability.

My invention is embodied in a cleat, the rear end portion of the body of which projects rearwardly from the two lateral spurs, and overlaps the ball portion of the tread 45 face, to protect said ball portion against wear, the body being oblong and its rearwardly projecting portion being provided with a spur located on the longitudinal median line of the body and constituting a supplemental ground-engaging means, supplementing the means provided by the front and lateral spurs.

Of the accompanying drawings forming a part of this specification,—

Figure 1 is a bottom plan view of a base-

ball shoe provided with my improved cleat.

Figure 2 is a fragmentary side view, shown partly in section on the plane indicated by line 2—2 of Figure 1.

Figure 3 is a perspective view of the improved cleat.

The same reference characters indicate the same parts in all of the figures.

The forepart of the shoe bottom shown by Figures 1 and 2, includes an outer layer 65 12, and an inner layer 13, the layer 12 being, in this instance, a tap whose outer side is the tread face of the forepart, while the layer 13 is a flexible sole member extending the full length of the shoe. The layers 12 70 and 13 may be attached to each other and to the shoe upper in any suitable way, and are stiffened by a thin steel plate 14, interposed between the layers, the rear portion of the plate being within the saliently 75 curved ball portion of the tread face, designated by 15. The forward portion of the plate extends nearly to the toe of the shoe bottom, and the major portion of the plate usually imparts a substantially flat form 80 to the bottom between the ball portion 15 and the toe, as shown by Figure 2.

The body 16 of my improved cleat is oblong, and formed to bear on the tread face of the forepart of the shoe bottom, and to 85 extend between two points on the longitudinal median line of said tread face, one point being adjacent the toe end of the tread face, and the other on the ball portion 15, as shown by Figures 1 and 2.

The cleat comprises ground-engaging spurs integral with the body and including a front spur 17, projecting from the front end of the body, a rear spur 18, projecting from the rear end of the body, the spurs 17 90 and 18 being on the longitudinal median line of the body, and two intermediate spurs 19, projecting from the body at opposite sides of the median line thereof.

The spurs 17 and 19 have the usual relative arrangement found in the ordinary cleat having a substantially triangular body, the rear end portion of which extends directly from one spur 19 to the other without projecting rearwardly from said spurs.

In my improved cleat the rear end portion of the body, and the rear spur 18 thereon, are extended rearwardly from the spurs 19, and are formed and arranged to overlap the curved ball portion 15, and prevent wear of 110

said ball portion, the rear spur 18 providing a supplemental ground-engaging means, supplementing the means provided by the spurs 17 and 19.

5 The body 16 is rigidly attachable as usual, by rivets 20, engaging the layers 12 and 13 and the stiffening plate 14, as shown by Figure 2.

10 The spurs 19, located between the ends of the oblong body, and between the end spurs 17 and 18, may be called intermediate spurs.

I claim:

15 A cleat for a baseball shoe, comprising an oblong body, and ground-engaging spurs integral with said body, including a front spur projecting from the front end of the body,

a rear spur projecting from the rear end of the body, said front and rear spurs being on the longitudinal median line of the body, and two intermediate spurs projecting from the body at opposite sides of the median line thereof, the rear end portion of the body and the rear spur thereon projecting rearwardly from the intermediate spurs and providing a supplemental ground-engaging means at the rear end of the cleat supplementing the means provided by the front and intermediate spurs, the body being rigidly attachable to a shoe bottom.

20 In testimony whereof I have affixed my signature.

DANIEL J. GOLDEN.
